UNITED STATES PATENT OFFICE

HENRY P. C. KEULS, OF NEW YORK, N. Y., ASSIGNOR TO SEALED JOINT CONSTRUCTION CORPORATION, A CORPORATION OF NEW YORK

WALL STRUCTURE

Application filed February 24, 1931. Serial No. 517,803.

This invention relates to wall constructions as made up of building blocks, such as bricks, tiles, stone or composition wall units, and the like, which are laid with mortar or other suitable binder material between them, forming joints, and the object of the invention is to seal the joints between the blocks in such a manner as to prevent the passage, seepage or penetration of water or moisture through the joints, either entirely or substantially so.

It has been found in the erection of walls of buildings, more particularly those in which bricks are used, that, due to the character or condition of the mortar of the joints between the bricks, or to the manner in which the mortar is applied or distributed, or to the amount used, or to other causes, water or moisture will penetrate and pass through the joints, more especially, where, in rain storms, the rain is driven by high winds against the face of the building. The water thus leaking through the front wall structure, enters the inner wall structure, and finally finds its way to the finished walls of rooms, and causes such damage thereto as to require in many cases, the entire refinish- 25 ing of the walls and other repairs, to the great inconvenience and discomfort of the occupants, as well as expense. In remedying this condition, it has been necessary for workmen to point up practically all of the joints in the front wall, and in large buildings now so frequently erected, the expense of such repair work is very great, as high in a recent 30 case within my knowledge, as \$250,000.00; and even then not entirely remedying the fault.

Under the present invention, means are provided for sealing, or practically sealing, the joints in the wall, against the passage or seepage of water therethrough, as the building of the wall progresses, which is effected by the incorporation in the joints, of sealing strips of suitable material, in such manner that these strips will, in cooperation with the mortar or other binder of the joints, form a barrier against the passage of the water therethrough, and will either entirely eliminate such passage of water, or reduce the same to a negligible minimum.

My invention therefore consists of the improved wall structure, which will be described in detail in the specification to follow, and the novel features of which will be pointed out in the appended claims.

55

In the accompanying drawings:

Fig. 1 is a front elevation of a portion of a wall embodying my invention, parts being broken away and other parts being shown in section, in order to better illustrate the invention;

60

Fig. 2 is a perspective view of one of the building blocks or bricks of which the wall is composed, showing the preferred form of the same which adapts it for use in carrying out the invention;

65

Fig. 3 is a perspective view of one of the sealing strips for incorporation in the horizontal joints between the courses of wall blocks;

70

Fig. 4 is a similar view of one of the sealing strips for the vertical joints between the individual blocks of the courses;

Fig. 15 is a fragmentary perspective view of one of the blocks, and a sealing strip of modified form applied thereto.

10 Referring to the drawings:

As best shown in Figs. 1 and 2, the wall structure embodying my invention is made up of courses of building blocks or bricks 1, preferably of the form shown in Fig. 2, where 15 it will be seen that the brick has formed in it a continuous open groove 2 extending entirely around it lengthwise and centrally thereof, thereby forming horizontal grooves 2^a in the upper and lower sides of the brick, 20 and vertical grooves 2^b in the ends of the same. When bricks of this form are laid end to end, in courses one above the other, with mortar 3, or other suitable binder material 25 between the bricks in building a wall of the form shown in Fig. 1, the end grooves of a brick will align with the end grooves of adjacent bricks, and the upper and lower grooves of the bricks of a course will align with the corresponding grooves of the bricks 30 of the adjacent courses, so that there will be produced, vertical composite grooves 4 between the ends of the individual bricks, and horizontal composite grooves 5 between the course of bricks. These composite grooves 35 communicate with the horizontal and vertical points respectively between the bricks, and are adapted to receive respectively, horizontal sealing strips 6, preferably of the form shown in Fig. 3, and vertical sealing strip 7, 40 preferably of the form shown in Fig. 4, which strips are embedded in the mortar of the respective joints and extend into the grooves of adjacent bricks, and therefore act in connection with the mortar of said joints as barriers or seals against the flow or seepage of 45 water through the joints.

These sealing strips may be made of any material impervious, or substantially impervious to water, such for instance, as copper or galvanized iron, or other appropriate material possessing this characteristic, and the vertical strips 7 are of a width to bridge the mortar joint between the ends of the bricks and to extend into and overlap the 55 walls of the aligned vertical grooves therein, while the horizontal strips 6 are similarly of a width to bridge the horizontal joints between the sides of adjacent bricks and to extend into and overlap the walls of the aligned 60 grooves in the sides of the adjacent bricks, all as best shown in Figs. 1, 12, 13 and 14.

As shown in Figs. 1, 5 and 9, the horizontal strips 6 overlap the upper and lower ends of the vertical strips 7, as at 8, and the adjacent 65 ends of the horizontal strips overlap each

other, see Figs. 5 and 9, thereby forming around each individual brick and in the vertical and horizontal joints, a continuous barrier made up conjointly of the vertical and horizontal overlapping strips embedded in 70 the mortar of the joints, and thereby constituting an effectual seal for said joints.

In erecting a wall to incorporate such sealing strips, the bricks of the first or base course are laid end to end, after having mortar applied to their ends to constitute the vertical joints between them, and in this position of the bricks, the grooves 2^a in the upper sides of the bricks will be exposed and will align with each other. A vertical sealing strip 7 is now inserted in each of the composite vertical grooves 8 between the ends of adjacent bricks and in the mortar therebetween, the length of these strips being such that they will project at their upper ends 80 a short distance above the upper faces of the bricks; and horizontal sealing strips 6 are placed in the aligned horizontal grooves 2^a of the several bricks of the course, and are preferably disposed as above mentioned, so that 85 they will overlap the upper projecting ends of the vertical strips, and their inner ends will overlap each other at points between the ends of the bricks, the upper edges of these strips projecting a short distance above the 90 upper faces of the bricks and substantially flush with the upper ends of the vertical strips; as shown in Fig. 1. A layer of mortar is now spread over the upper faces of the 95 bricks so as to cover the projecting portions 100 of the horizontal and vertical sealing strips, and sufficient in quantity to constitute the horizontal joint between the two courses. Another course of grooved bricks is now laid 105 on this bed or layer of mortar and lined up with the bricks of the first course, and the workman by tamping the bricks down slightly, will cause the upper projecting edges of the strips to be received in the grooves in the 110 undersides of the bricks; and these operations are continued in laying the bricks of the succeeding courses. As a result, the vertical and horizontal sealing strips will be embedded in the mortar of the joints, and 115 will extend into the grooves of adjacent bricks and into the mortar therein, which mortar will enter to a greater or lesser extent into said grooves as it is applied to the ends and sides of the bricks, as above described.

“Header” bricks 10 for incorporation with “stretcher” bricks in walls of the so-called American or Flemish bonds, as illustrated respectively in Figs. 9 and 10, will be constructed of the form shown in Fig. 8, where it will be seen that three continuous grooves 11 extend around the brick transversely thereof, so that when these “header” bricks are laid alongside each other as shown in Fig. 9, as in the American bond, or are alternated with “stretcher” bricks, as in the 120 125 130

Flemish bond, as shown in Fig. 10, the horizontal portions of the front transverse grooves of the "header" bricks will align with the longitudinal grooves of adjacent "stretcher" bricks to receive the horizontal sealing strips, and the vertical portions of the front grooves of the "header" bricks will align with the vertical grooves in the sides of similar "header" bricks, or the vertical grooves in the ends of adjacent "stretcher" bricks, to receive the vertical sealing strips.

In the use of this "header" brick, only the front end groove of the three shown will function, if sealing strips are employed in the first wall only; but in the event that the second or inner wall is built with sealing strips, the other end grooves of the "header" bricks will function similar to the first. The central groove in the "header" brick is for the purpose of enabling the brick-layer to separate the brick into two equal sections for use in certain kinds of brick work.

On reference to Figs. 5 and 6, it will be seen that the wall structure there shown embodies two angularly related walls 13, joining each other in a corner, and to adapt the invention to this corner portion of the wall, I propose to employ in some cases an L-shaped corner block or brick 14 as shown in Fig. 6, where it will be seen that horizontal grooves 14^a are formed in the upper and lower sides of the brick, which grooves intersect at their inner ends at each side of the brick, and vertical grooves 14^b are formed in the ends of the brick. The location of these grooves is such that the end grooves will align with the end grooves of adjacent bricks when the L-shaped brick is laid in the corner of the wall, as shown in Fig. 5, and the side grooves 40 of the L-shaped brick will align with similar grooves in similarly L-shaped bricks when these bricks are laid one upon the other; or will align with the side grooves of "stretcher" bricks when the latter are alternated vertically with the L-shaped bricks.

Angular sealing strips 16, preferably of the form shown in Fig. 7, may be used to seat in the angularly related grooves 14^a of the L-shaped bricks, as shown in Fig. 5, the ends of which angular strips will overlap the ends of the straight horizontal strips 6 seated in the horizontal grooves of adjacent "stretcher" bricks; or in place of such an angular strip, two straight strips may be seated in the angularly related grooves and be abutted at their inner ends to form a sealed corner.

It will be manifest that instead of employing horizontal sealing strips of a length to extend only from one block or brick to another, as hereinbefore shown and described, longer strips may be employed, so as to take in three or a greater number of bricks, without departing from the limits of the invention.

The use of the term "building blocks" in

the claims is intended to be generic to all forms of block-like building units, such as bricks, blocks of stone or composition stone, or the like, solid or hollow tiles, etc., etc., and the invention is applicable, as will be obvious, to such different forms of building blocks or units to seal the mortared joints between them, although the invention has especial and peculiar application to building blocks in the form of bricks.

Also the use in the claims of the term "mortar" in defining the material of which the joints between the bricks are composed, is meant to include also all other forms of binder material, such as cement, concrete, or other compositions in which building blocks may be laid in the formation of wall structures; and the use of such other materials is clearly within the scope of the invention as expressed in the claims hereof.

While in the foregoing description and accompanying drawings I have set forth the invention in the particular detailed form which I prefer to adopt, in respect to the construction of the parts, it will be understood that these details may be variously changed and modified by the skilled mechanic without departing from the limits of the invention; and further, it will be understood that the invention is not limited to any particular form or construction of the parts, except in so far as such limitations are specified in the claims.

It may be advisable in order to maintain the horizontal strips in upright position in the horizontal grooves in the bricks, before the mortar is applied, to provide the strips with horizontal supporting pins 17 in position to rest on the upper face of the brick at the sides of the groove, as shown in Fig. 15. These pins will act to prevent the strip from falling sidewise in the groove out of proper position.

Having thus described my invention, what I claim is:

1. In a wall construction, the combination of courses of building blocks disposed one over the other and each block provided with a continuous groove extending entirely around the same lengthwise thereof, the grooves of adjacent blocks being aligned with each other both at the sides and ends of the same, mortar between the ends and sides of adjacent blocks and constituting vertical joints between the individual blocks and horizontal joints between the courses of blocks, vertical sealing strips embedded in the mortar of the vertical joints and extending into the grooves in adjacent blocks to seal said vertical joints and horizontal sealing strips embedded in the mortar of the horizontal joints and extending into the grooves in the sides of the blocks to seal said horizontal joints.

2. In a wall construction the combination

of building blocks laid end to end in courses, said blocks being provided in their sides and ends with grooves, with the grooves of one block in alignment with the corresponding 5 grooves of the adjacent block, mortar between the blocks forming vertical joints between the individual blocks of a course, and horizontal joints between the courses of blocks, vertical sealing strips embedded in 10 the mortar of the vertical joints and extending into the aligned end grooves of adjacent blocks, and horizontal sealing strips embedded in the mortar of the horizontal joints and extending into the aligned side 15 grooves of adjacent blocks, said horizontal strips overlapping the ends of the vertical strips.

3. In a wall construction, the combination of building blocks laid end to end in courses, 20 said blocks being provided in their sides and ends with grooves, with the grooves of one block in alignment with the corresponding grooves of the adjacent block, mortar between the blocks forming vertical joints between 25 the individual blocks of a course, and horizontal joints between the courses of blocks, vertical sealing strips embedded in the mortar of the vertical joints and extending into the aligned end grooves of adjacent blocks, and 30 horizontal sealing strips embedded in the mortar of the horizontal joints and extending into the aligned side grooves of adjacent blocks, said horizontal strips overlapping the ends of the vertical strips, and the said horizontal strips overlapping each other at their 35 ends.

4. In a wall structure, the combination of angularly related walls made up of grooved building blocks having mortar between them 40 and having horizontal and vertical sealing strips embedded in said mortar and extending in the grooves, L-shaped building blocks at the corner of said walls, provided each in its upper and lower sides with angularly related horizontal grooves adapted to align with 45 the grooves in adjacent similar L-shaped blocks and horizontal angular sealing strips adapted to be seated in the aligned angular grooves and to be embedded in the mortar 50 between the said blocks, said L-shaped blocks being provided in their ends with vertical grooves aligned with the vertical grooves of adjacent building blocks, and vertical sealing strips seated in said aligned vertical 55 grooves and embedded in the mortar between the blocks.

5. In a wall construction, the combination of courses of building blocks disposed one over the other and each block provided with 60 a continuous groove extending entirely around the same, the grooves of adjacent blocks being aligned with each other, binder material between the blocks constituting vertical joints between the individual blocks and 65 horizontal joints between the courses of

blocks, vertical sealing strips embedded in the binder material of the vertical joints and extending into the grooves in adjacent blocks to seal said vertical joints, and horizontal sealing strips embedded in the binder material of the horizontal joints and extending into the grooves in adjacent blocks to seal said horizontal joints.

In testimony whereof, this specification has been duly signed by:

HENRY P. C. KEULS.
